KNITTING MACHINE

Benjamin F. Coile, Athens, Ga., assignor of one-half to Paul Keller, Athens, Ga.

Application June 3, 1937, Serial No. 146,142

10 Claims. (Cl. 66—107)

This invention relates to knitting machines and more especially to the web holding mechanism of such machines.

An object of this invention is new and novel means for lubricating the web holders and yieldingly holding them in position for free reciprocation.

In known web-holding mechanism, a web holder ring has radial slots in which are arranged the web holders for reciprocation by a rotated cam. Each web holder has a portion for engagement with the bottom of the web holder ring to prevent vertical movement of the holders by the knitting needles.

Heretofore, it has been customary to lubricate the web holders and needles merely by pouring oil on to the web-holder ring which is very objectionable due to the fact that there is nothing to prevent the oil from running off with the result that the web holders and needles run dry and become hot, causing excessive wear and the formation of a black substance which, when the mechanism is again oiled, is wiped off on the fabric. The present invention obviates the conditions above described and, according to the invention, the web-holder ring is provided with an annular groove in which is arranged a felt wick which is engaged by the inner ends of the web holders. The felt wick is saturated with oil and reciprocation of the holders causes application of lubricant to the sides as well as the bottom of the holders with transfer of some of the lubricant to the needles. The thorough lubrication of the holders and needles prevents them from becoming hot and minimizes the wear.

Other objects, novel features and advantages will become apparent from the following specification and accompanying drawing, wherein:

Fig. 1 is a vertical section through a web-holding mechanism embodying the invention;

Fig. 2 is a plan view of the web-holder ring;

Fig. 3 is an enlarged fragmentary section through the web-holder ring showing a web holder in elevation, and

Fig. 4 is a fragmentary perspective view of the web holder ring.

The needle cylinder 10 is provided with exterior grooves 11 in which are arranged needles 12. A web holder bed 13 is tightly fitted on a flange 14 formed on the needle cylinder 10. As is usual in the art, the bed 13 is radially grooved at 15, the last-named grooves being spaced between the needle grooves 11. On the bed 10 is rotatably mounted a web-holder cam ring 16 having a flange 17 for engagement with the

butts 18 of the web holders 19 arranged in the grooves 15.

A web holder ring 20 fits tightly into the upper end of the needle cylinder 10 and has an exteriorly turned flange 20' to rest upon the top edge of the needle cylinder. This ring 20 also has a substantial flange 21 extending outwardly from an upper part thereof and providing a pair of spaced parallel bearing surfaces 22 and 23. The bearing surface 22 is provided by the bottom surface of flange 21 and the surface 23 forms part of the top of the ring 20. The body of the flange 21 has an upstanding portion 21' which is substantially triangular in cross section, the hypotenuse of the triangle extending downwardly and inwardly, whereby a downwardly and inwardly inclined surface is provided. The part 21' is provided with a plurality of radial slots 24 to receive the web-holders and the body portion of flange 21 is provided with the slots 24' for 20 the needles 25.

As is well understood, ring 20 supports a plurality of web holders 25 for movement radially of said ring, and guides them during their movement in and out. These web holders are each 25 provided with an upper arm 26 which passes through the slots 24 and rests upon the upper bearing surface 23, and a lower arm 27 which moves under the flange 21 with its upper surface engaging the under bearing surface 22. This 30 arrangement of arms and bearing surfaces and slots insures proper movement of the web holders during operation.

I provide an annular groove 28 in the upper surface of ring 20 and provide a wick 29 of felt 35 or other suitable material in said groove. It is to be noted that the wick 29 is located near the inner ends of the radial slots 24 in the web holding ring 20 and near the bottom of the inclined surface 30 of the slotted portion of said ring. 40 Any suitable lubricant is used to saturate the wick 29. The arm 26 of the web holder 25 engages the wick 29 and as it reciprocates across the wick, it is lubricated. Some of the lubricant is carried by the web holders through the grooves 24 and supplied to the needles. Thus both the web holders and needles are thoroughly lubricated thereby preventing them from becoming hot and minimizing wear. Also, the wick 29 45 serves to yieldingly hold the arm 26 in position tending to prevent canting of the web holder by pull exerted from the needles 12. The wick, therefore, not only serves to effect lubrication of the web holders and needles, but also minimizes 50 55

the possibility of binding of the arms 26 and 27 against the surfaces of the flange 21.

The above-described arrangement provides a highly efficient and inexpensive device for effecting thorough and uniform lubrication of the web holders and needles. The wick retains sufficient lubricant for a long period of operation and reduces waste of lubricant to a minimum. It is one advantage of the arrangement that no additional mechanism is required for the knitting machine as it is necessary only to provide a groove in the web holder ring adjacent the inner ends of the web holder grooves. The thorough and uniform lubrication of the web holders and needles insures that they do not become unduly heated and thereby wear is minimized. Also, the above-described arrangement prevents damage to the fabric from deposits thereon of black substance resulting from improper lubrication.

It is of course understood that various modifications may be made in the above-described web-holding mechanism without in any way departing from the spirit of the invention as defined in the appended claims.

I claim:

1. In a knitting machine, a web-holder ring having radial slots for receiving the web holders, said ring having an annular groove adjacent the inner ends of said slots, and a lubricating wick arranged in said groove.

2. A web holder mechanism comprising a ring having radial slots for receiving web holders, and an annular lubricating wick supported by said ring for simultaneous engagement by web holders in said slots.

3. In a knitting machine, a web-holder ring having a flange provided with radial slots for receiving the web holders and provided with upper and lower plane surfaces of which the former is adjacent the inner ends of said slots and has an annular groove, web holders in said slots and being recessed to provide upper and lower arms engaging said surfaces, and a lubricating wick in said groove engaged by said upper arms.

4. In a knitting machine, a web holder ring having radial slots for receiving web holders, said ring having an annular groove, web holders in said slots and a lubricating wick in said groove engaged by said web holders.

5. A web holder mechanism comprising a ring

having a slotted flange provided with an annular surface coplanar with the bottoms of said slots, a groove in said annular surface, a lubricating wick in said groove and web holders in said slots engaging said wick.

6. In a knitting mechanism, an exteriorly grooved cylinder, needles in the grooves, a ring carried by said cylinder and having radial slots, web holders in said slots, each web holder being arranged between two needles, and an annular lubricating wick supported by said ring for simultaneous engagement by said web holders.

7. In a knitting mechanism, an exteriorly grooved cylinder, needles in the grooves, a ring carried by said cylinder, said ring having radial slots and being provided with upper and lower planar surfaces of which the former is adjacent the inner ends of said slots, web holders in said slots and being recessed to provide upper and lower arms engaging said surfaces, and a lubricating wick supported by said ring for engagement by said upper arms.

8. In a knitting mechanism, an exteriorly grooved cylinder, needles in the grooves, a ring carried by said cylinder, said ring having a slotted flange provided with an annular surface coplanar with the bottoms of said slots, a groove in said annular surface, a lubricating wick in said groove and web holders in said slot engaging said wick.

9. In a knitting mechanism, an exteriorly grooved cylinder, needles in the grooves, a ring carried by said cylinder, said ring having a slotted flange provided with upper and lower plane surfaces of which the former is adjacent the inner ends of said slots and has an annular groove, a lubricating wick in said groove, and web holders in said slots, said web holders being recessed to provide upper arms engaging said upper surface and wick and lower arms engaging said lower surfaces.

10. In a knitting mechanism, an exteriorly grooved cylinder, needles in the grooves, a ring carried by said cylinder, said ring having a slotted flange provided with an annular surface adjacent the inner ends of the slots, a lubricating wick supported by said flange and web holders in said slots, said web holders having portions engaging said surface and said wick.

BENJAMIN F. COILE.
